UNITED STATES PATENT OFFICE.

EDWARD H. RIESMEYER AND GEORGE H. SCHAFER, OF PITTSBURGH, PENNSYLVANIA.

HEATING FURNACE.

Application filed September 29, 1921. Serial No. 504,103.

To all whom it may concern:

Be it known that we, EDWARD H. RIESMEYER and GEORGE H. SCHAFER, residing at Pittsburgh, in the county of Allegheny and State of Pennsylvania, citizens of the United States, have invented or discovered certain new and useful Improvements in Heating Furnaces, of which improvements the following is a specification.

10 The invention described herein relates to certain improvements in hot air furnaces and has for its object a construction permitting of not only the independent use of solid and fluid fuels but also the simultaneous use of such fuels when rendered necessary by extremely cold weather. The invention is hereinafter more fully described and claimed.

In the accompanying drawings forming 20 a part of this specification, Fig. 1 is a sectional elevation of a furnace embodying the improvement claimed herein; Fig. 2 is a sectional plan view, the plane of section being indicated by the line II—II, Fig. 1; 25 Fig. 3 is a sectional elevation on a plane at right angles to Fig. 1; Fig. 4 is a sectional plan view on a plane indicated by the line IV—IV, Fig. 3, and Fig. 5 is a sectional plan view on a plane indicated by 30 the line V—V, Fig. 1.

The portion of the heater in which the solid fuel is burnt, may be constructed in any suitable manner known in the art, the construction shown herein consisting of 35 a fuel pot 1 and fire pot or crab section 2, detachably supported on the fuel pot, and a smoke box or as it is usually termed in the art, the radiator. This radiator consists of a central portion 3 which is an extension of the fire pot, and a tubular annular portion 4 surrounding but spaced from the portion 3 and connected thereto by a radial flue 5. By reference to Figs. 1 and 4 it will be seen that the nozzle 6 40 through which gases from the radiator escape to the pipe 7 leading to the chimney, is located diametrically opposite the point of connection of the flue 5 to the annular radiator. This construction causes a 45 division of the gases, into two streams which are afterwards united as they flow through the nozzle 6.

The fire pot is provided with a box-like extension 8 through which fuel is fed to 50 the furnace. Below the fuel pot is arranged an ash box 9 having a lateral ex-

tension 10 for the removal of ashes, etc., from the box 9.

Headers 11 formed on arcs of circles which preferably have their centers coincident with the axis of the fuel and fire boxes, are arranged on opposite sides of the fuel box and in approximately horizontal alignment with the lower portions of the fuel box. These headers are connected by 65 a plurality of vertical tubes 12 with similar headers 13 arranged outside of the annular flue 4, or radiator, as shown in Figs. 1, 3 and 4. Burners 14 for fluid fuel are arranged within the lower headers and are 70 adapted to be connected by pipes 15 to a suitable source of supply. These headers are provided with openings 16 to permit access to the burners to light the fluid fuel and for inspection purposes. The upper 75 headers are provided with nozzles 17 for connection with pipes 18 leading to a chimney flue.

A casing 19 is arranged outside of the headers, said casing extending from the 80 base of the furnace to a suitable distance above the heating elements, forming a chamber 20 from which the heated air will escape through pipes 21. Cold air is introduced into the lower portion of the casing 85 through a pipe 22.

By reference to Figs. 1, 2, 3, and 4, it will be seen that the elements heated by the combustion of fluid fuel are spaced a substantial distance from the pot in which 90 solid fuel is burnt and that the annular flue or radiator 4 is so located in the upper portion of the space between the surfaces heated respectively by the two fuels that the air is brought into intimate contact 95 with the surfaces of the annular flue. The spaces between the casing and the elements heated by the fluid fuel is small relative to the inner air chamber so that the flow through the latter will be greater and will 100 cause air flowing up along the casing to pass between and around the tubes connecting the headers.

Where only a relatively small degree of heat is required, only the fluid fuel will be 105 used, but where a higher degree is required, coal will be used, the fluid fuel burners being turned out unless a maximum heat is needed.

It will be observed that separate outlets 110 are provided for the products of the combustion of the two fuels, and in installing

the furnace the pipes 7 and 18 should be connected to independent flues in the chimney as where the products from combustion of coal and a fluid fuel are brought together, the larger volume of the coal products will smother the other flame.

We claim herein as our invention:

1. A heating furnace having in combination a chamber for the combustion of coal, headers arranged outside of and spaced a suitable distance apart from the walls of said chamber, tubes connecting said headers, a burner for fluid fuel arranged in said headers and independent means for carrying the combustion products to independent flues in the chimney.

2. A heating furnace having in combination

a chamber for the combustion of coal, an annular smoke flue or radiator arranged above said chamber, upper and lower headers arranged outside said chamber, and annular flue respectively, and spaced therefrom, a plurality of tubes connecting the headers, burners for fluid fuel arranged in the lower headers, and independent outlets for products of combustion from the annular flue and the upper headers said outlets being connected to independent flues in the chimney.

In testimony whereof, we have hereunto set our hands.

EDWARD H. RIESMEYER.
GEORGE H. SCHAFFER.
